Atty.

UNITED STATES PATENT OFFICE.

CHARLES E. BAILEY, OF PROVIDENCE, RHODE ISLAND.

WIRE NAIL.

SPECIFICATION forming part of Letters Patent No. 340,692, dated April 27, 1886.

Application filed January 4, 1886. Serial No. 187,627. (No model.)

To all whom it may concern:

Be it known that I, CHARLES E. BAILEY, a citizen of the United States, residing at Providence, in the county of Providence and State of Rhode Island, have invented certain new and useful Improvements in Wire Nails; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The nature of my invention relates, primarily, to the production of an improved wire nail, escutcheon-pin, and other similar articles; and it consists in forming a nail or pin having a shank provided with an alternate series of longitudinal ridges and channels its entire length from head to point; also forming a head upon said shank, partaking substantially of the form or configuration of the shank, substantially as hereinafter more fully described, and particularly pointed out in the claims.

Figures 1 and 3 are perspective views of my improved nail. Figs. 2 and 4 represent cross-sections of the same. Fig. 5 is a side elevation of my improved nail provided with a rounded head.

In carrying out my invention the nail A is made from wire, consisting of the head b and shank a, the latter being formed with an alternate series of longitudinal ridges, c, and channels e its entire length, from head to point, as fully shown in the drawings.

The ridges and channels are formed on the shank by proper machinery, and may be formed of a variety of shapes, Fig. 1 showing concave channels and convex ridges, and Fig. 3 angular forms, these two shapes being preferred by reason of the simplicity of construction.

The shank a may be provided with the 45 ridges c and channels e previous to heading, in which case the edge d of the head will approximate substantially the form or configuration of the shank, thus producing various ornamental effect without additional cost. 50

The shank a may be headed in the usual manner of escutcheon-pins, as shown in Fig. 5.

By means of my improvement I am enabled to produce a nail which will remain in the material into which it is secured without 55 danger of turning laterally, this being an especial advantage in furniture-nails where it is desirable to have all the heads remain in a like position as at first driven in. The nail is also stronger with less weight of metal, as 60 the ridges serve to strengthen or brace the shank against a lateral strain in driving, which is a great advantage over the plain shank nails now in use. The shank is pointed to readily enter material. The variety of forms of ridges 65 and channels which may be employed render the formation of any particular shape of head easily accomplished with less cutting and trimming than at present, and a strong and durable article is thus furnished at a small cost. 70

I claim—

1. A nail made from wire and provided with longitudinal ridges and channels, said nail being provided with an integral head of substantially the same configuration as the 75 shank, substantially as herein set forth.

2. The nail A, consisting of the shank a, provided with the longitudinal ridges c and channels e, and provided with the head b, having corresponding ridges and channels, substantially as described. 80

In testimony whereof I affix my signature in presence of two witnesses.

CHARLES E. BAILEY.
